(57) **CLAIM**

The ornamental design for a lamp for use with computer desk, as shown.

DESCRIPTION

FIG. 1 is a front elevational view showing my new design;
FIG. 2 is a rear elevational view thereof;
FIG. 3 is a left side elevational view thereof;
FIG. 4 is a right side elevational view thereof;
FIG. 5 is a top plan view showing thereof;
FIG. 6 is a bottom plan thereof
FIG. 7 is a perspective view thereof; and,
FIG. 8 is a reference view showing my new design under the state of use.

The broken lines showing the paper holder and desktop fastener in FIG. 8 are illustrative of environmental structure only and form no part of the claimed design.
